UNITED STATES PATENT OFFICE.

DAVID LEAVITT HOUGH, OF NEW YORK, N. Y., ASSIGNOR TO ALBERT WELLS BUEL AND THE UNITED COMPANY, OF SAME PLACE.

DESIGN FOR A CHANNEL-BAR FOR TUNNEL OR SIMILAR CASINGS.

SPECIFICATION forming part of Design No. 31,371, dated August 8, 1899.

Application filed June 28, 1899. Serial No. 722,198. Term of patent 14 years.

To all whom it may concern:

Be it known that I, DAVID LEAVITT HOUGH, a citizen of the United States, residing in the borough of Manhattan, in the city of New York, in the county of New York and State of New York, have invented and produced a new and original Design for Channel-Bars for Tunnel-Casings, of which the following is a specification, reference being had to the accompanying drawings, forming part thereof.

Figure 1 is a perspective view of a channel-bar for tunnel-casings, showing my new design. Fig. 2 is a side view of the same. Fig. 3 is a transverse sectional view.

As shown in the drawings, the leading or material feature of my design consists of the rib *r*, arranged near or adjacent to one edge of the web or body *b* upon the side or surface opposite from two projecting edge wings *c* and *c'*, respectively, said rib *r* being arranged in parallel relation to a rib *a*, projecting at the opposite edge of the web or body *b* and from the same face as the rib *r* and forming a continuation or extension of one of said edge wings *c*. The rib *r* projects at right angles to the web *b* and extends longitudinally with relation to the same. The edge rib *a* likewise projects at right angles to the web *b* and extends longitudinally with relation to the same. The ribs *r* and *a* thus extend in parallel relation and in general correspond, the rib *a* being at the edge of the web, while the rib *r* is located some distance from or within the edge plane of the opposite edge of the web. The wings *c* and *c'* project at right angles to the web *b* at the side opposite from the ribs *r* and

a and extend longitudinally at the respective edges of the web.

The outer faces of the respective ribs and wings are flat, as shown at *f*, while the inner faces of said ribs and wings are curved or rounded toward their outer ends, as shown at *f'*. The flat face of the rib *a* and the flat face of the wing *c* thus conjointly form a continuous flat face at the edge of the channel-bar opposite from the wing *c'* and the rib *r*. The rib *a* projects in a direct plane corresponding to the plane of the wing *c*, while the rib *r* and the wing *c'* project in different but parallel planes. The web is in a continuous straight transverse plane between the rib *a* and the wing *c* and the opposite wing *c'*, its continuous outer surface being broken only by the rib *r*.

The channel-bar, including the web and the ribs and wings, is segmentally curved, as shown, so that the wings project from the concave inner face and the ribs project from the convex outer face.

Having described my invention, what I claim as new, and desire to secure by Letters Patent, is—

The design for a channel-bar for tunnel and similar casings, substantially as herein shown and described.

In testimony whereof I have hereunto set my hand, in presence of two witnesses, this 15th day of June, 1899.

DAVID LEAVITT HOUGH.

Witnesses:
